CURRENT-POLARIZED GROUND-DIRECTIONAL RELAY FOR PARALLEL LINES

Bernard E. Lenehan, Bloomfield, N. J., assignor to Westinghouse Electric & Manufacturing Company, East Pittsburgh, Pa., a corporation of Pennsylvania

Application April 18, 1939, Serial No. 268,531

3 Claims. (Cl. 175—294)

My invention relates to protective relaying systems for transmission lines, and it has particular relation to the ground-directional relay elements for systems involving two grounded three-phase transmission lines which are parallel to each other for some distance, so as to have a material amount of zero-phase-sequence coupling, the two lines having relaying points at a common substation, and both being grounded at said substation.

An object of my invention is to provide novel means for preventing a faulty response of a current-polarized ground-directional relay, for such a system, in response to inductively induced ground currents, which flow "in" on the line and "down" in the ground-connection, and which produce the same directional effect, in the relay, as "actual" ground-currents which flow "out" on the line and "up" in the ground-connection.

A more specific object of my invention is to polarize the ground-directional element with a current which is responsive to the sum of both of the currents in the ground-connections for both of the aforementioned mutually coupled lines, thus always obtaining a correct polarizing direction because the actual ground-currents in the faulted line are always larger than the induced ground-currents in the clear line.

With the foregoing and other objects in view, my invention consists in the systems, combinations, methods and apparatus hereinafter described and claimed, and illustrated in the accompanying drawing, the single figure of which is a simplified diagrammatic view of circuits and apparatus embodying my invention in a preferred form.

In the drawing, my invention is illustrated as being embodied in a three-phase transmission system involving two separate three-phase transmission lines L_1 and L_2 , which extend, for some distance, parallel to each other, in close juxtaposition, as indicated, so as to have a material zero-phase-sequence coupling. The two lines L_1 and L_2 each have an end in a common substation, as illustrated, where the line L_1 is illustrated as being connected, through a circuit breaker CB_1 , and delta-star step-up power transformers PT_1 , to a generator or generators G_1 ; while the line L_2 is similarly connected to a generator or generators G_2 through a circuit breaker CB_2 and power transformers PT_2 . The star windings of the respective power transformers PT_1 and PT_2 are the high-voltage windings which are connected to the respective lines L_1 and L_2 , and these star-connected transformer windings

have their neutral circuits grounded, as indicated, to provide grounding connections for the respective lines L_1 and L_2 .

The circuit breaker CB_1 of the line L_1 is provided with a trip coil TC_1 which is energized in response to a ground-directional element DO_1 and an over-current ground-relay IO_1 . The ground-directional element DO_1 is provided with two sets of terminals, which may be referred to 10 as the directional terminals and the polarizing terminals, respectively, so that the directional-element compares the relative directions of the currents in the two terminals. The operating coil of the ground overcurrent relay IO_1 and the directional terminals of the ground-directional relay DO_1 are energized with the neutral current of a bank of star-connected line-current transformers CT_1 , which are illustrated as also supplying current to line-current-responsive devices 20 A_1 , B_1 and C_1 .

The circuit breaker CB_2 of the second line L_2 is likewise provided with a trip coil TC_2 which is controlled by a ground overcurrent relay IO_2 and a ground directional relay DO_2 , which are 25 similarly energized from line-current transformers CT_2 , which also supply phase-current-responsive relaying loads A_2 , B_2 and C_2 .

In accordance with my invention, the polarizing terminals of the two ground-directional elements DO_1 and DO_2 are energized in accordance with the sum of the currents in the grounded neutral points of the star-connected windings of the respective power transformers PT_1 and PT_2 . This energization is obtained with the aid of 30 auxiliary neutral-current transformers NT_1 and NT_2 , respectively, connected in the grounded neutrals of the two banks of power transformers PT_1 and PT_2 , the secondary coils of these neutral current-transformers NT_1 and NT_2 being connected in parallel, in order to obtain the sum of the grounded-neutral currents, in accordance 35 with my invention.

In operation, let it be assumed that there is 40 ground-fault somewhere out on the first line L_1 , as indicated at X in the drawing. This will produce zero-phase-sequence line-currents I_{01} , which may be regarded as flowing "out," on the line L_1 , and "up," in the ground-connection of the power transformers PT_1 . By reason of the 45 zero-sequence coupling between the two lines, the zero-phase-sequence ground-fault current I_{01} in the faulted line L_1 will induce, in the other line L_2 , a somewhat smaller, oppositely flowing zero-phase-sequence current I_{02} , which flows 50 "in," on the line L_2 , and "down," in the grounded 55

neutral connection of the power transformers PT2.

If the ground-directional relay DO2 of the second line L2 were polarized simply with the current in the grounded neutral of the power transformers PT2, as was heretofore common in the art, this directional element would respond to the above-mentioned induced currents, the same as if the ground-fault were on the line-section side of the relaying point, because the directional-element cannot distinguish between currents flowing in and down, and currents flowing out and up.

In accordance with my invention, however, the polarizing terminals of either one or both of the directional elements DO1 and DO2 are energized in accordance with the sum of the two grounded-neutral currents, so that they will be responsive to an upwardly flowing grounded-neutral resultant in every case, no matter whether the ground-fault is on the line L1 or the line L2. In this manner, a directional response is obtained only in response to "actual" residual line-currents which are flowing in such a direction as to indicate that the ground fault is on the line-current side of the relaying point, the directional elements being quite unresponsive to the oppositely flowing "induced" residual line-currents.

While I have illustrated my invention in a preferred form of embodiment, it will be obvious that many changes, such as those which have been suggested during the course of the description, and other changes not alluded to, may be made by those skilled in the art, without departing from the essential features of my invention. I desire, therefore, that the appended claims shall be accorded the broadest construction consistent with their language and the prior art.

I claim as my invention:

1. In combination, two grounded polyphase transmission lines having a material amount of zero-sequence coupling therebetween, and having relaying points at a common relaying station, ground directional relaying-means, at said station, for at least one of said lines, said directional relaying-means having two sets of terminals for comparing the relative directions of the respective currents therein, a set of star-con-

nected line-current transformers associated with said one of the lines for energizing one of said sets of terminals responsive to the neutral current therein, means for so energizing the other set of terminals as to be additively responsive to the sum of zero-sequence components in the two lines, and means responsive to the condition of said relaying-means when a ground fault occurs on said one of said lines for interrupting service on said one of said lines.

2. In combination, two polyphase transmission lines having a material amount of zero-sequence coupling therebetween, and having relaying points at a common relaying station, separate grounded star-connected means for the two lines at said station, ground directional relaying-means, at said station, for at least one of said lines, said directional relaying-means having two sets of terminals for comparing the relative directions of the respective currents therein, a set of star-connected line-current transformers associated with said one of the lines for energizing one of said sets of terminals responsive to the neutral current therein, means for energizing the other set of terminals additively in response to the ground-currents in the grounded star-connected means on both lines, and means responsive to said relaying-means for interrupting service on said one of said lines.

3. Means for determining on which side of a grounding point, in a protected grounded polyphase transmission line, a ground-fault may be located, under circumstances where said line is, at least to a material extent, paralleled by another grounded polyphase transmission line having a grounding point at the same location, said means comprising the combination, with said lines, of means for obtaining a response to the zero-phase-sequence component of the line-current in the protected line, means for deriving a reference-current comprising at least two additively combined components responsive, respectively, to the ground-currents in the two grounding points, and means for comparing the relative direction of said zero-phase-sequence component with respect to said reference-current.

BERNARD E. LENEHAN.
